M. A. MILLER

SASH LOCK AND HOLDER

Filed Dec. 3, 1921

UNITED STATES PATENT OFFICE.

MOSES A. MILLER, OF ST. ALBANS, VERMONT.

SASH LOCK AND HOLDER.

Application filed December 3, 1921. Serial No. 519,750.

To all whom it may concern:

Be it known that I, MOSES A. MILLER, a citizen of the United States of America, and resident of St. Albans, in the county of Franklin and State of Vermont, have invented certain new and useful Improvements in Sash Locks and Holders, of which the following is a specification.

This invention relates to windows, and particularly to sash locks therefor, the said invention having for an object the provision of novel means whereby a sash may be held in closed position and preferably associated with means for holding the window elevated at different positions of adjustment.

A further object of this invention is to provide a sash lock or holder, the operating parts of which may be concealed and made inaccessible, in order that they cannot be tampered with by unauthorized persons.

A still further object of this invention is to produce a sash lock and holder of the character indicated which will prove effective and durable and which will not mar the appearance of the window or parts thereof.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a sash showing the frame and parts associated with it in section;

Figure 2 illustrates a view in elevation of the sash and frame showing the latch operating parts in elevation;

Figure 3 illustrates a sectional view on a line corresponding with the line 3—3 of Fig. 2;

Figure 4 illustrates a view in elevation of the latch and plate;

Figure 5 illustrates a view in perspective of the latch detached; and

Figure 6 illustrates a perspective view of a latch retaining spring.

In these drawings 10 denotes a sash having a plate 11 constituting a face of its edge, the said sash having a series of recesses 12 forming seats for irregularly shaped offset portions 13 of the said face plate. The off-

set portions 13 have shoulders 14 with outwardly inclined walls merging with the outer surface of the face plate, and the said face plate also has an offset portion 15 with a shoulder 16 at the bottom, the said shoulder 16 being inclined from the surface of the face plate to the inner edge or wall of the said recess for the purpose of engaging a latch, as will presently appear, to prevent the sliding of the sash.

The latch or dog 17 is oscillatable on a pivot 18 carried by the housing 19 which is imbedded in the sash frame 20 with relation to which the sash slides. The dog has a nose 21, the lower edge of which is shaped to the contour of the shoulder 16, in order to form an interlocking engagement therewith which will prevent camming of the nose of the dog with relation to the socket of the face plate, even though pressure is applied to the sash from below. The upper edge of the nose of the dog is approximately straight and it is adapted to be engaged by any one of the shoulders 14 when the sash is elevated, and the dog is then effective to hold the sash in different positions of adjustment. A lug 22 on the upper end of the dog abuts an inner wall of the housing and serves to retain the dog in position against the action of a spring 23, which spring is operative to force the free end of the dog normally outward. The spring has an angularly disposed foot 24 which fits in a recess 25 of the housing whereby it is anchored in operative relation to the dog.

The dog 17 is pressed inwardly to force the nose out of any one of the recesses of the face plate by a push rod 26 slidable through the sash frame, the inner end of the said push rod engaging an arm 27 which is integral with the dog. If desired, the push rod may be removably applied to the frame so that when the sash is held locked, there will be nothing exposed which might be manipulated by unauthorized persons for the purpose of operating the dog.

The housing is of such construction as to form a seat for the spring, as fully shown in Fig. 1, and it is believed that one skilled in the art will understand that the action of the dog will be such as to hold the sash locked when the parts are in the positions shown in Fig. 1, whereas when the dog is pushed inwardly, the sash may be elevated and it will also be understood that the dog

will serve to engage one of the shoulders 14 of the face plate and retain the sash at different positions of adjustment.

I claim:

- 5 1. In a sash lock and holder, a sash having a face plate with recesses formed therein with shoulders at the upper ends of the recesses and a recess having an inclined shoulder at its lower end, a dog pivotally mounted in a window casing and having a nose projecting therefrom adapted to enter the recesses of the face plate, the said dog having a lower edge adapted to engage the inclined shoulder of one of the recesses and 15 a straight upper edge adapted to engage the shoulders of the other recesses, means for urging the nose of the dog into operative relation with the said shoulders, a laterally extending arm carried by the dog, 20 and manually operated means engaging the arm for pushing the dog against the action of the said urging means.
2. In a sash lock and holder, a sash having a face plate with recesses formed therein with shoulders at the upper ends of the recesses and a recess having an inclined shoulder at its lower end, a dog pivotally mounted in a window casing and having a nose projecting therefrom adapted to enter the recesses of the face plate, the said dog having a lower edge adapted to engage the inclined shoulder of one of the recesses and 25 30

a straight upper edge adapted to engage the shoulders of the other recesses, means for urging the nose of the dog into operative 35 relation with the said shoulders, a laterally extending arm on the said dog, and a push rod slideable through the casing into engagement with the arm for pushing the dog against the action of its urging means. 40

3. In a sash lock and holder, a sash casing having a housing therein open at the edge of the sash, a dog pivotally mounted in the casing and having a nose projecting from the edge of the frame, a spring anchored in the casing and bearing against the dog to hold it normally outward, an inclined surface on the lower edge of the nose of the dog and a straight surface on the upper edge of the nose, a sash having recesses, a face plate attached to the edge of the sash and having irregular contour fitting the recesses of the sash, an inclined shoulder forming the lower wall of one of the irregularities of the face plate, shoulders at the upper ends of the other irregularities of the face plate and inclined surfaces therebelow merging with the outer surface of the plate with relation to which the nose of the dog coacts, and means for pushing the nose of the dog out of engagement with the face plate. 45 50 55 60

MOSES A. MILLER.
